CLAIM

The ornamental design for a closure of a fluid trap for a respiratory therapy device as shown and described.

DESCRIPTION

FIG. 1 is a front, top, and left side perspective view of a closure of a fluid trap for a respiratory therapy device embodying our new design;

FIG. 2 is a front, bottom, and left side perspective view thereof;

FIG. 3 is a top view thereof;

FIG. 4 is a bottom view thereof;

FIG. 5 is a left side view thereof;

FIG. 6 is a right side view thereof;

FIG. 7 is a front view of thereof; and,

FIG. 8 is a rear view of thereof.
